UNITED STATES PATENT OFFICE.

SWITS CONDÉ, OF OSWEGO, NEW YORK.

DESIGN FOR A KNIT FABRIC.

SPECIFICATION forming part of Design No. 12,318, dated June 21, 1881.

Application filed April 23, 1881. Term of patent 7 years.

To all whom it may concern:

Be it known that I, SWITS CONDÉ, of Oswego, in the county of Oswego, in the State of New York, have invented a new Design for 5 Knit Shirts and Drawers, of which the following, taken in connection with the accompanying drawings, is a full, clear, and exact description.

This design consists in a novel arrangement 10 of alternate dark and light mottled stripes wrought in knit shirts and drawers vertically in relation thereto.

In the accompanying drawings, Figure 1 represents a body of a knit shirt wrought in 15 accordance with my design, and Fig. 2 is an enlarged detail view of a piece of the fabric of which said shirt is composed.

a and *b* denote the dark and light mottled stripes respectively. Said stripes are formed 20 of two or more differently-colored yarns knitted in such a manner as to cause one of them to

predominate to a certain degree over the other alternately at the surface of the fabric, and at the same time bring the said stripes vertically in relation to the garment, as illustrated in 25 Fig. 1 of the drawings.

What I claim is—

The design for a knit fabric to be used for shirts and drawers, consisting of dark and light mottled stripes arranged alternately and 30 vertically in relation to the garment, substantially as shown and described.

In testimony whereof I have hereunto signed my name and affixed my seal, in the presence of two attesting witnesses, at Oswego, in the 35 county of Oswego, in the State of New York, this 19th day of April, 1881.

SWITS CONDÉ. [L. S.]
